UNITED STATES PATENT OFFICE.

FRANK W. MEYER, OF OSHKOSH, WISCONSIN, ASSIGNOR TO THE OSHKOSH TRUNK COMPANY, OF OSHKOSH, WISCONSIN, A CORPORATION OF WISCONSIN.

WARDROBE TRUNK.

Application filed February 14, 1921. Serial No. 444,664.

To all whom it may concern:

Be it known that I, FRANK W. MEYER, a citizen of the United States, residing at Oshkosh, in the county of Winnebago and 5 State of Wisconsin, have invented new and useful Improvements in Wardrobe Trunks, of which the following is a specification.

This invention relates to wardrobe trunks adapted for land or sea travel.

10 One object of my invention is to provide a wardrobe trunk so constructed that it may be placed flat on one side under a bunk or berth of a steamship when used in sea travel and by opening a hinged lid at the exposed 15 end of the trunk enable convenient access to be had to all the garments or other articles packed in the trunk to be taken out and placed back in the trunk without at any time removing the trunk from under 20 the berth, and thus cause the trunk to occupy none of the available space in the stateroom.

Another object of my invention is to construct the trunk so that it may be placed 25 upright on one end and opened up like a customary center opening wardrobe trunk when used in travel on land, thus rendering the trunk capable for land as well as water travel.

30 Other and further objects of the invention will appear from the following specification, taken in connection with the accompanying drawings, in which—

Fig. 1 is a perspective view of a trunk 35 constructed in accordance with my invention and shown placed under a bunk or berth of a steamship with the lid at one end of the trunk open to permit access to be had to the garments and articles packed in 40 the trunk without removing the trunk from under the berth, and illustrating how the trunk is used when traveling on water or sea;

Fig. 2 is an enlarged longitudinal sectional view taken through the trunk when 45 lying on one side and with its end lid open, as shown in Fig. 1;

Fig. 3 is an enlarged fragmentary vertical sectional view of the locking mechanism 50 for the lid and taken on line $a-a$ of Fig. 4;

Fig. 4 is a perspective view of the trunk standing upright on one end, closed and locked, and illustrating how the trunk may 55 be used in the manner of a wardrobe trunk when traveling on land;

Fig. 5 is a perspective view of the trunk open, when used like a wardrobe trunk;

Figs. 6 and 7 are perspective views of two of the boxes or containers, removed from the trunk;

Fig. 8 is an enlarged fragmentary vertical sectional view taken along the line 8—8 of Fig. 5; and

Fig. 9 is a perspective view of another 65 of the boxes or containers removed from the trunk.

The trunk shown in the drawings is constructed along the general lines of a center opening wardrobe trunk. It has two hinged sections 1 and 2, both of which have open 70 ends at one and the same end of the trunk. To close these ends, when the sections 1 and 2 are closed, I provide a lid 3 hinged to the section 1 and extending over and closing the open ends of both sections when the lid 75 is closed, as shown in Fig. 1.

The section 2 has side cleats 4, 4 extending endwise thereof and these, together with the back and two side walls of the section, form a channel to receive a rectangular 80 tray 5 provided with extensible trolleys 6 for the garment hangers 7. This tray also has a clothes retainer 8 and the usual fixtures that are provided for releasably and adjustably holding that part in position in 85 the tray. The tray 5 has a length and width substantially equal to the like dimensions of the section 2 and is slidably mounted in said section, and the latter having an open end permits the tray 5 to be 90 withdrawn endwise therefrom to remove the tray completely from the trunk when the lid 3 is opened. This also permits the tray to be slid endwise back into the section 2 through its open end when replacing 95 the tray in the trunk. To facilitate withdrawing the tray 5 from the section 2, the tray is provided at its open end with a pull tab 9, preferably in the form of a loop to permit convenient grasping thereof and 100 also allowing the tray to be hung up on a hook or nail in a closet or room when it is out of the trunk.

In the other section 1 is arranged a plurality of box like containers 10, 11, and 12. 105 When the trunk is placed upright on its lower end, as shown in Fig. 5, these containers are one above the other with the uppermost container 10 supported on cleats 13 secured to the side walls of the section 1, 110

and are prevented from sliding out through the open side of the section 1 by a cross-bar 14 extending across the section at its open end and secured to the side walls thereof, as shown in Fig. 5. This cross-bar 14 also acts as a brace to prevent inward or outward bulging of the open end of the section. The box 10 has a hinged lid 15 held closed by snap or other fasteners on flexible locking tabs 16, and may be withdrawn out through the open end of the section by grasping the flexible finger loops 17 at the ends of the box, as best shown in Fig. 6.

The intermediate box or container 11 is supported in the section 1 by cleats 18, and this container has laterally projecting side flanges 19 to engage against the front faces of stop cleats 20 extending between the supporting cleats 13 and 18, as shown in Fig. 8, so as to prevent the container when placed in section 1 from being pushed back against the rear wall thereof.

The innermost or bottom box or container 12 rests on the bottom or end wall of the section 1 and it also has side flanges 21 to engage against stop cleats 22 aligned with the other stop cleats 20. Through one of these side cleats 22 extend the fixed locking members or eyes 23 of the trunk locking mechanism, these eyes being secured to the adjacent side wall of the section 1 and when the trunk sections 1 and 2 are closed together, these eyes extend through apertures or holes 24 in one of the side cleats 4 of the section 2 and are in position to be engaged by the movable locking members 25, which, as shown in Fig. 2, are in the form of hooks pivoted in the section 1 and connected with an endwise movable bar 26. This bar is connected by a crank arm 27 with the locking hasp 28 rotatably mounted on the outside of the section 2 adjacent the lid 3, as shown in Figs. 4 and 5. This locking mechanism is the same as disclosed in my Reissue Patent No. 14,143, granted May 30, 1916. The locking hasp 28, as in my said prior patent, has a hinged section 29 carrying the key operable tumbler lock mechanism, and in the trunk shown herein is adapted to engage the socketed plate 30 secured on the outside of the lid 3 at one side thereof.

The adaptability of the trunk for sea travel will now be explained. In Fig. 1, I have shown a ship's berth 31, of the type usually found in staterooms on seagoing and other steamers. The berth usually extends the full width of the stateroom and of course is spaced above the floor. The trunk of my invention is made so that it may be inserted under the berth and rest on the floor on one of its flat sides. The lid 3 being hinged to the section 1, makes it necessary to place the trunk under the berth with the flat side of the wardrobe section 2 on the floor. When so positioned, the lid 3 is unlocked by un-

locking the hasp 29 and swinging it out of the socket 30, whereupon the lid is raised into an upright position, as shown in Fig. 1. Before this can be done, however, the brace rod 32 is slipped off of the fixed stud 34 on the inside of the lid 3, and the rods 32 and 33 are then folded one on the other and pushed back out of the way into the section 1 alongside of the now outermost container or box 10. When the lid is opened and raised as mentioned, access is permitted to the wardrobe carrying tray 5 and the several garment carrying containers or boxes 10, 11, and 12 without being required to withdraw the trunk from beneath the berth, or open its sections 1 and 2, or set it upright on end.

To gain access to the garments on the hangers in the tray 5, the pull tab 9 is grasped and the tray slid endwise out of the open end of the section 2 until it is free of the trunk, whereupon it may be lifted and stood against the wall of the room or be hung up by the tab 9 on a hook and the garments on the hangers may be readily reached for use. To have access to the first box 10, it is pulled endwise out of the section 1 by grasping the finger loops 17 and this then allows the next container 11 to be reached so as to be slid out of the open end of the section 1. The container 11 has a pivoted bail or handle 35 which may now be grasped and the container pulled out of the open end of the section 1 and be removed from the trunk for use. To reach the innermost container 12, the user of the trunk could reach it through the open end of the section 1 and grasp its pivoted bail or handle 36 for sliding it out of the trunk, but to facilitate reaching this container, it is brought into position for ready grasping of its handle 36 by the pull rod 37. This is slidably mounted against the back wall of the section 1 in guide straps 38, 38, as shown in Fig. 2. The rod 37 has its inner end 39 bent to engage back of the box 12, and has its outer end 40 bent outward to provide a suitable grasping handle or flange for pulling or moving the rod endwise outward through the open end of the section 1. The rod extends the full length of this section and when all of the containers are in the section the handle end 40 is against the adjacent edge of the section and does not interfere with or prevent the closing of the lid 3. When the containers 10 and 11 have been withdrawn from the section 1 in the manner described, the handle end 40 of the rod is then grasped and the rod given a quick sharp pull outward, this causing the innermost container 12 to be drawn toward the open end of the section 1 into about the position shown in full lines in Fig. 2, whereupon the user of the trunk can readily reach the handle or bail 36 on the end of the box 12 and withdraw it through the open end of the section 1 and remove it

120
125
130

from the trunk to gain access to the contents within it. These boxes 11 and 12 rest and slide on the side edges on stop cleats of the section 2.

5 To pack the trunk while under the berth, it is not necessary to remove the trunk from under the berth. All that is required is that the lid 3 be swung open into position above the trunk, as shown in Figs. 1 10 and 2, and the tray 5 slid back into the section 2 and the several containers or boxes 10, 11 and 12 slid back into the section 1, whereupon the lid may be swung into closed position and the locking hasp 29 15 swung into locking engagement with its keeper or socket 30, and the trunk is locked and ready for the porter.

When traveling on land there is no occasion for using the trunk in the manner 20 as when on shipboard, because there is usually plenty of room for standing the trunk up on its lower end and opening up the sections 1 and 2 by unlocking them and swinging them apart, as shown in Fig. 5. 25 To unlock the trunk, the hasp 28 is unlocked from its keeper 30 and then rotated downward into the position shown in dotted lines in Fig. 4. This moves the hooks 25 out of the eyes 23 for unlocking the sections 1 and 30 2 on the inside. This also unlocks the lid 3. When the sections 1 and 2 are opened, access may be readily had to the garments on the hangers in the tray 5 without sliding the tray endwise out of the open upper end of the section 2, as the trolleys 6 may be extended outward and the retainer 8 removed in the same manner as in a customary wardrobe trunk. Access may now 35 readily be had to the now upper container 40 or box 10 without withdrawing it through the open upper end of the section 2, by merely unfastening the lid 15 and raising it into open position. The middle container 11 may be slid out through the now 45 open side of the section 1 by grasping the flexible pull tab 41 and pulling it clear out of the trunk section. It may be placed anywhere in the room and access had to the contents packed in it by opening its lid 42 50 after unlocking the fastening tabs 43 with which the container is provided. The lid may be held or supported in open position by a rod 44 pivoted on one of the partitions 45, as shown in Fig. 7. This rod is swung 55 down into position alongside of its adjacent partition when the lid is to be closed and locked. There are several of these partitions 45, as shown in Fig. 7, which divide the container into several compartments 60 for receiving shoes or such other articles as may be packed therein, and the partitions are removably mounted in the container by having their edges in guideways formed by strips secured to the container walls, as illustrated in Fig. 7.

To permit the container or box 11 to be supported in the manner of a drawer projecting outward from the section 1, I provide a slideway 46 to receive the slide flanges 19 of the container when the latter is horizontally arranged and slid into the section 1 in this slideway. This supports the container in horizontal position, as shown in Fig. 8, and access may be had to it at that time by opening the lid 42, as is apparent. 70 These slideways 46 are formed by the cleats 18 and an upper set of cleats 47. The now lowermost container 12 may be pulled out of the section 1 by means of a pull tab 48 on its bottom wall, as shown in Fig. 5. 75

When the trunk is used as a land trunk, that is, used in travel on land, it is used like an ordinary wardrobe trunk, and of course the tray 5 may be pulled endwise out of the section 2 and be hung up in a closet or stood against the wall of a room, if that is desirable, although ready access may be had to the garments in the tray without removing it from the trunk. The lid 3 when raised is held in an upright position, as shown in Fig. 5, and prevented from swinging back by the brace rods 32, 33, the former 32 being at such time engaged with the stud 34, shown in Fig. 2.

To provide additional compartment facilities for the trunk, there is a container 49 pivoted in the lid 3 and, when not in use, held back in the lid by a fastening tab 50. This hinged compartment 49 has a suitably hinged lid, which is held in closed position 90 by fastening tabs as shown in Fig. 1.

To securely lock the lid 3 closed, I provide a locking mechanism operating in conjunction with the main trunk locking device as described. This locking mechanism comprises an endwise movable bar 51 located in the lid 3 and extending across the same and slidably mounted in cleats 52. One end of the bar extends into the socketed member 30 for the hasp 28 and the other end is 100 adapted to project into a recess 53 in the lid 3, as shown in Fig. 5. Secured to one of the side walls of the section 2 and projecting beyond the open end thereof is a lug 54 having at its outer end an eye 55, as shown 110 in Fig. 1, to receive the adjacent end of the locking rod 51. About the latter is a coiled spring 56 bearing at one end against one of the cleats and at the other end against a pin on the bar and in a direction to constantly 120 urge the bar toward the locking hasp 29. When the locking hasp 29 is unlocked, the spring 56 moves the rod 51 outward against the hasp, thereby assisting in moving it into open position and at the same time withdrawing its opposite end from the eye in the lug 54, thereby unlocking the lid 3 at that 125 end of the trunk. When the locking hasp 29 is swung into its keeper socket 30, it pushes against the bar 51 and moves its opposite 130

end into the eye in the lug 54, thereby effecting the locking of the lid at opposite sides of the trunk section 2, at one point by means of the locking hasp 29 and at the other 5 point by means of the bar 51 and lug 54. This locks the lid 3 at opposite sides of the trunk and therefore locks it securely closed and prevents that corner opposite the locking hasp from springing outward from the 10 trunk, which might happen if there were no locking bar 51 provided for that purpose.

While I have shown and described in detail herein a trunk constructed in accordance with my invention, it is of course to be understood that the various details of construction may be variously changed and modified without departing from the spirit and scope of my invention.

I claim as my invention:

20. 1. A wardrobe trunk, comprising two hinged together sections open at their upper ends, garment retaining means in each of said sections and accessible through the open inner sides of the sections when the latter are 25 swung apart and the trunk standing upright on its lower end, said means being slidably mounted in their respective sections to be slid out of and into the same through their open ends when the sections are closed and 30 the trunk lying flatwise on one of the same, means for closing the open ends of said sections in either position of the trunk, and locking means for said sections and the closing means for the open ends thereof.

35. 2. A wardrobe trunk, comprising two hinged together sections open at their upper ends, a lid for closing the open ends of said sections and hinged to one of the same, a tray in one of said sections and containing 40 fixtures for garment hangers, a plurality of box like containers in the other section, the garment hangers in the tray and the containers in the other section being accessible through the open inner sides of said sections 45 when the lid is raised and the sections are swung apart with the trunk standing upright on its lower end, said tray and containers being slidably mounted in their respective sections to be slid out of and into 50 the same through their open ends when the sections are closed and the trunk lying flatwise on one of the same with the lid raised, means for locking said lid closed in either position of the trunk, and locking means for 55 said sections.

60. 3. A wardrobe trunk, comprising two hinged together sections open at their upper ends, a lid for closing the open ends of said sections and hinged to one of the same, a tray in one of said sections and containing fixtures for garment hangers, a plurality of box like containers in the other section, the garment hangers in the tray and the containers in the other section being accessible 65 when the lid is raised and the sections swung

apart when the trunk is stood upright on one end, said tray and containers being slidably mounted in their respective sections to be slid out of and into the same through their open ends when the trunk is closed and 70 lying flatwise on one section with the lid raised, and locking means for said sections and lid, said locking means permitting the lid to be locked and unlocked while the trunk is lying flatwise and without unlocking said sections. 75

4. A wardrobe trunk, comprising two hinged together sections open at their upper ends, a lid for closing the open ends of said sections and hinged to one of the same, a tray in one of said sections and containing fixtures for garment hangers, a plurality of box like containers in the other section and arranged one behind the other, the garment hangers in the tray and the containers in the 80 other section being accessible when the lid is raised and the sections swung apart when the trunk is stood upright on one end, said tray and containers being slidably mounted in their respective sections to be slid out of and into the same through their open ends when the trunk is closed and lying flatwise on one section with the lid raised, means accessible from the open end of the trunk to draw the innermost container toward the 85 open end of its section to be reached, and locking means for said sections and lid. 90

5. A wardrobe trunk, comprising two hinged together sections, both open at one end, a lid for closing said sections and hinged to one of the same, a tray slidably mounted in one of said sections and provided with fixtures for garment hangers, said tray being slideable endwise into and out of its section through the open end 100 thereof when the lid is raised, a plurality of box like containers slidably mounted in the other section and adapted to be withdrawn from and inserted back into said section 105 through the open end thereof when the trunk is closed and lying down flatwise on one section and the lid raised, a pull rod slidably mounted in the section containing said containers and having its inner end engaging the innermost container behind the 110 same and its outer end accessible from the open end of the section to permit said innermost container to be drawn toward the open end of said section after the other containers 115 have been withdrawn from said section, and locking means for locking the sections and lid closed. 120

6. A wardrobe trunk, comprising two hinged together sections, both open at one end, a lid for closing said sections and hinged to one of the same, a tray slidably mounted in one of said sections and provided with fixtures for garment hangers, said tray being slideable endwise into and out of said 125 section through the open end thereof when 130

said lid is raised, a plurality of box like containers slidably mounted in the other section and being one above the other when the trunk is set upright on one end with the 5 lowermost container resting on the bottom wall of its section and the other containers supported by cleats secured to the side walls of said section so that the containers may be removed independently from said section 10 through the open side thereof when the trunk is upright and the sections swung apart, additional cleats secured to the side walls of the container section above the cleats for the intermediate container to provide 15 slideways, said intermediate container having side flanges to enter said slideways and support the container in a substantially horizontal position projecting outward through the open inner side of the section 20 when the trunk is upright, and locking means for locking the sections and lid closed.

7. A wardrobe trunk, comprising two hinged together sections, one of said sections being open at its upper end, a hinged 25 lid for closing said open end, garment retaining means in each of said sections and accessible through the open inner sides of the sections when the latter are swung apart and the trunk standing upright on one end, 30 the garment retaining means in the open ended section being slidably mounted in said section to be withdrawn from and inserted back into the same through the open end thereof when the sections are closed and the 35 trunk lying flatwise on one of said sections with said lid open, and locking means for said lid and sections.

8. A wardrobe trunk, comprising two hinged together sections, one of said sections being open at its upper end, a hinged lid for closing said open end, garment retaining means slidably mounted in the open 40 ended section and adapted to be completely withdrawn from and inserted back into said 45 section through the open end thereof when

the sections are closed together and the lid open, and locking means for said lid and sections.

9. A trunk, comprising two hinged together sections, one of said sections being open at its upper end, a hinged lid for closing said open end, a plurality of garment retaining boxes slidably mounted in said open ended section and arranged one behind the other, said boxes being withdrawn from 50 and inserted back into said section through the open end thereof when the lid is open, locking means for said lid and sections, and means carried by the open ended section and accessible when the lid is open to draw the 55 innermost container toward the open end of said section to be reached for withdrawal.

10. A trunk, comprising two hinged together sections, a plurality of garment retaining boxes slidable into and out of one 60 of said sections through an opening at one end thereof, a pull rod slidably mounted in said section, said rod having its inner end engaging the innermost box and its outer end accessible from the open end of said 65 section for bringing the innermost box within reach from the open end of said section after the other boxes have been removed, a lid for the open end of said section, and locking means for said lid. 70

11. A trunk, comprising two hinged together sections, garment retaining means in each of said sections, said means being slidably mounted in their respective sections and adapted to be withdrawn from and inserted back into the trunk through openings provided in said sections when the sections are closed together, one of said sections having its opening at one end, a lid for closing said opening, and locking means for said lid 80 and sections. 85

In testimony that I claim the foregoing as my invention, I affix my signature, this 11th day of February, A. D. 1921.

FRANK W. MEYER.
